CHAIR STRUCTURE

Alfred C. Hoven and William S. Lindberg, Grand Rapids, Mich., assignors to American Seating Company, Grand Rapids, Mich., a corporation of New Jersey

Application May 24, 1947, Serial No. 750,336

6 Claims. (Cl. 155—184)

1

The present invention relates to chair structures of the type used in motor busses, railway coaches and the like.

The primary objects of the invention are to provide an upholstered chair structure having means on the back panel thereof for receiving and retaining a display card having advertising material thereon, so that when the chair structures are installed in vehicles in the usual manner one behind another, the occupant of one such structure will view the advertising material on the rear of the chair structure in front of him; to provide stamped sheet metal means for removably mounting a display card or panel on the rear surface of a stamped sheet metal chair back panel, the construction being such that the parts are easily and inexpensively fabricated and assembled; to provide such a structure in which, although the back is inclined upwardly-rearwardly for the comfort of the chair occupant, the display panel is in a more nearly vertical position thus to facilitate the reading of copy on the display card by the occupant of the chair to the rear; and to provide such a chair structure in which the display panel and the frame therefor are so mounted on the back panel that there are no projecting parts to snag the clothing of persons occupying or vacating the chair structure to the immediate rear thereof.

These objects are attained by the illustrative embodiments of the invention shown in the accompanying drawing, wherein:

Figure 1 is a rear perspective view of a chair structure of the type which is commonly installed in city busses, and showing a panel mounted on the rear thereof bearing the inscription "Display" in lieu of advertising material;

Figure 2 is an enlarged, fragmentary, vertical sectional view of the same taken on line 2—2 of Figure 1;

Figure 3 is a fragmentary rear elevational view of a bus chair back with a display panel mounted thereon, the construction here shown being a modification of that shown in Figures 1 and 2;

Figure 4 is a sectional view thereof taken on line 4—4 of Figure 3; and

Figure 5 is an enlarged, fragmentary, vertical sectional view thereof taken on line 5—5 of Figure 3.

Referring now in detail to this drawing and referring first particularly to the construction shown in Figures 1 and 2, the bus chair there shown generally comprises a frame 10 and legs 11 of tubular metal construction, having a con-

2

ventional upholstered seat 12 and an upholstered back 13 secured to the tubular frame by any convenient means such as welding or screw fastenings (not shown). The chair back 13 and the tubular metal frame supports therefor are inclined upwardly rearwardly for the comfort of the chair occupant, the angle of inclination being usually about 15 to 20 degrees from vertical.

The chair back panel 14 on which the upholstered chair back is built, is of stamped sheet metal construction having a forwardly and inwardly turned flange 15 around its edges, and having a forwardly drawn recess 16 therein, the top wall 17 of which recess 16 is substantially horizontal as here shown and the front wall 18 of which recess is inclined upwardly-forwardly relative to the main body of the back panel, said front wall 18 being nearly vertical as here shown.

As best seen in Figure 2, a display panel frame 20 is mounted on the rear surface of the front wall 18 of the recess 16, and said frame comprises a pair of horizontal flange members 19, 20 secured as by welding to the front wall of the recess and having portions 21, 22 respectively which extend rearwardly and then toward each other thus forming complementary, parallel upper and lower grooves into which may be slid a panel 23 bearing an advertisement or other material to be displayed.

Upholstery padding 24 of cotton, hair, moss or the like is disposed over the front surfaces of the back panel 14 including the top and front walls of the recess 16, and an upholstery covering 25 of leather, fabric or the like is disposed over the padding and secured at its edges to the edges of the back panel 14. Preferably the padding 24 and covering 25 are pre-assembled to a wooden frame 26 by means of tacks 27, and the unit thus made is assembled to the back panel 14 by means of wood screws 28 passing through apertures in the back panel and threaded in the wooden frame 26 thus lending a neat appearance to the back.

In Figures 3—5 inclusive is shown a slightly modified form of frame for the display panel 23. In this construction, the front wall 18¹ of the recess 16¹ of the back panel 14¹ has a plurality of tongue-receiving apertures 30 therethrough. The panel frame has tongues 31 at its rearward top and bottom, which tongues are inserted forwardly through the apertures 30 and are then bent over and spot welded to the front surface of the front wall 18¹ of the back panel 14¹, and the display panel frame is thus rigidly secured to the chair back panel. In this construction, the

panel frame is one integral, stamped sheet of metal, the parallel, rearwardly and inwardly extending, complementary flanges 19^1 and 20^1 of which are connected by end strips $32, 33$ which complete the framing for the display panel. The right hand end strip 33 is desirably provided with a forwardly extending tongue 34 which is projected forwardly through an aperture 35 in the back panel and which is bent over and spotwelded to the back panel similarly to the tongues 32 . The rearward portion of this tongue 34 serves as a stop for properly positioning the display panel 23^1 in the panel frame. The display panel 23^1 is flat and slightly flexible so that it may be slidingly inserted in the recess 16^1 as seen at the left of Figure 4.

In both of the embodiments of the invention hereinbefore described, it will be seen that the padding of the back is diminished in the region of the back panel's recess. There remains, however, sufficient padding between the front wall of the recess and the upholstery covering so that the difference could not be detected by the chair occupant and this is especially so because of the location of the recess near the top of the back. It will also be seen that the display panel is easily readable by an occupant of the chair in the rear of that shown, because of the near vertical position of this display panel, and that the back of the chair presents a smooth surface having no objectionable protruding parts.

While but two specific embodiments of the invention have been herein shown and described it will be understood that other modifications might be conceived without departing from the spirit of the invention as the same is defined by the following claims.

We claim:

1. In a chair structure, in combination: a back panel having an upholstered chair back on the front side of the back panel and a recess in the rear side of the back panel extending forwardly therefrom, and a pair of complementary, parallel flanges on the rear side of the back panel within said recess adapted to slidingly receive and retain a display panel therebetween.

2. In a chair structure, in combination: an upwardly-rearwardly inclined back panel having an upholstered chair back on the front side of the back panel, said back panel having a forwardly extending recess in its rear side and the front wall of the recess being inclined upwardly-forwardly relative to the main body of the back panel, and display panel retaining means mounted on the front wall of the recess.

3. In a chair structure, in combination: an upwardly-rearwardly inclined sheet metal back panel having a forwardly extending recess therein in the front wall of which recess extends upwardly-forwardly relative to the main body of the back panel, upholstery padding over the front surfaces of the back panel including the front wall of said back panel's recess, an upholstery cover-

ing over the padding having its edges secured to the edges of the back panel, and a display on the rear surface of the front wall of the recess.

4. In a chair structure, in combination: an upwardly-rearwardly inclined sheet metal back panel having a forwardly extending recess therein in the front wall of which recess extends upwardly-forwardly relative to the main body of the back panel, upholstery padding over the front surfaces of the back panel including the front wall of said back panel's recess, an upholstery covering over the padding having its edges secured to the edges of the back panel, and display panel retaining means mounted on the front wall of the recess.

5. In a chair structure, in combination: a sheet metal back panel having an upholstered chair back on the front side of the back panel and having a plurality of tongue-receiving apertures therethrough, and a sheet metal frame on the rear side of the back panel for receiving a display panel, said frame comprising upper and lower flanges extending rearwardly from the back panel and then toward each other and adapted to slidingly receive and retain a display panel therebetween, and tongues on said frame inserted forwardly through said apertures and bent over for securing the frame to the back panel.

6. In a chair structure, in combination: an upwardly-rearwardly inclined sheet metal back panel having a forwardly extending recess therein the front wall of which recess extends upwardly-forwardly relative to the main body of the back panel and said front wall having a plurality of tongue-receiving apertures therethrough, a sheet metal frame mounted on the rear surface of the front wall of said recess for receiving a display panel, said frame comprising upper and lower flanges extending rearwardly from the back panel and then toward each other and adapted to slidingly receive and retain a display panel therebetween, tongues on said frame inserted forwardly through said apertures and bent over for securing the frame to the back panel, upholstery padding over the front surfaces of the back panel including the front wall of said back panel's recess, and an upholstery covering over the padding having its edges secured to the edges of the back panel.
